UNITED STATES PATENT OFFICE.

ARTHUR J. RAY, OF CHICAGO, ILLINOIS, ASSIGNOR, BY MESNE ASSIGNMENTS, TO
AUTOMATIC ELECTRIC INC., OF CHICAGO, ILLINOIS, A CORPORATION OF DELA-
WARE.

AUTOMATIC TELEPHONE SYSTEM.

Application filed December 1, 1924. Serial No. 753,016.

This invention relates in general to automatic telephone systems, but more especially to automatic systems of relatively small size, commonly known as private automatic exchanges.

Systems of the above character have been standardized for installation at points where individual lines only are in service and owing largely to this fact they are relatively simple and inexpensive. Another type of system, known as a community automatic exchange, has been developed for use in places where the service is more or less of a mixed character and especially where there are a large number of rural lines in service. Code ringing is required to signal the stations on rural lines and the community automatic exchanges therefore are characterized by the use of more or less complicated code ringing connectors, which are somewhat expensive. Now it may happen sometimes that a small automatic exchange is to be installed at a point where there are only a very few rural lines in service, from which it will be understood that the private automatic exchange, as distinguished from the community automatic exchange, would be entirely satisfactory and the most economical provided some special means could be provided, in addition to the ordinary equipment, for signalling the stations on the rural lines.

The object of the present invention, therefore, is to provide a new and improved device, an individual rural line repeater, whereby a plurality of substations on a rural line can be rung selectively by means of codes controlled by the dial at the calling station, thus dispensing with code ringing connectors and making it possible to use the ordinary private automatic exchange in situations to which it otherwise would not be applicable.

The above pointed out object, together with others not specifically mentioned at this time, will be pointed out and explained more fully hereinafter, reference being had to the accompanying drawings, in which—

Fig. 1 is a circuit diagram of an automatic substation A, rotary type line switches C and C', and connector repeater D.

Fig. 2 is a circuit diagram of an individual line repeater R and three magneto local battery substations A', A² and A³ on

the same line, the latter two having only their bells shown.

Proceeding now to the detailed explanation of the circuit drawings and referring first to Fig. 1, the automatic telephone substation A is connected in bridge of a pair of talking conductors and is arranged for straight line ringing. As represented herein, substation A comprises essentially the receiver 2, switch-hook 3, transmitter 4, condenser 5, bell 6, and calling device 7. The line conductors 11 and 12 of the substation A terminate at the central office in the individual line switch C and when a call is originated at the substation A, substation A is given access, through the medium of the line switch, to a plurality of connector repeater switches one of which is shown as D.

The individual line switches, of which the line switch C is typical, are mechanically of the rotary type and the wipers have no normal position and move in a forward direction only.

The connector repeater D is mechanically of the well known vertical and rotary type of switch and has its bank contacts arranged in ten horizontal rows or levels. Its circuit is arranged so as to enable the switch to operate as a local connector for the first nine levels, but to be non-rotary and to switch and repeat on the tenth or "0" level.

Referring to Fig. 2, the substations A', A² and A³, the latter two of which have only their bells shown, are in bridge of the line, are of the magneto local battery type arranged for simplex dialling, and are capable of being rung by either the individual station hand generators or the common generator GEN. As represented herein, substation A' comprises essentially the receiver 162, switch-hook 163, transmitter 164, bell 165, calling device 166, induction coil 167 and local battery 168. The line conductors 151 and 152 of the substations A', A² and A³ terminate at the central office in the individual line repeater R and when a call is originated at the substation originating same is given access, through the medium of the individual line repeater R and line switch C', Fig. 1, to a plurality of connector repeater switches, such as D.

The individual line repeaters, such as R, consist essentially of a plurality of relays, a repeating coil I, together with associated

common ringing generator GEN. to deliver the desired ringing current, and suitable circuits for performing the necessary functions, as will be pointed out hereinafter.

- 5 Having briefly explained the purpose of the invention and the apparatus involved in carrying it out, the operation of the equipment may now be explained more in detail. For this purpose it will be assumed that the 10 subscriber at station A, Fig. 1, desires to obtain connection with the subscriber at station A', Fig. 2. In order to do this, the subscriber at A removes his receiver and dials the directory number of the subscriber at A', 15 which we will assume to be 04-0. The first two digits of this number, it may be explained, are those which control the line selection, while the last digit is for code ringing.
- 20 When the receiver is removed at substation A, a circuit is completed over the line conductors 11 and 12 for the line relay 13 of the line switch C. Upon energizing, the line relay 13 closes at its armature 16 a circuit 25 which includes the switching relay 14 and the stepping magnet 15 in series, and at its armature 17 connects the test wiper 22 to the above circuit at a point midway between the switching relay and the said magnet. The 30 operation now depends upon whether the trunk line with which the wipers of the line switch C are associated is busy or is not busy. If the trunk line is busy the test contact with which the test wiper 22 is in engagement will be grounded, and as a result the switching relay 14 will be short circuited and the stepping magnet 15, being supplied with direct ground by way of the test wiper, 35 will operate as a buzzer to advance the switch wipers step by step in search of an idle trunk line. It may be assumed, in this case, that when the call is initiated the wipers of the line switch C are rotated until they come to rest on the bank contacts of the 40 trunk line shown in the drawing, and it may be assumed furthermore that the trunk line extending from these bank contacts is idle. Under these circumstances the test contact 45 50 will have no ground potential upon it and when the receiver is removed the energization of the line relay 13 is followed immediately by the energization of the switching relay 14. It may be stated at this point that the switching relay is of high resistance 55 so as to prevent the operation of the stepping magnet 15 at this time. As a result of the energization of the switching relay 14 the line conductors 11 and 12 are disconnected from the line relay 13 and from 60 ground, respectively, and are extended by way of armatures 18 and 20, wipers 21 and 23, and bank contacts 24 and 26 to the upper and lower windings of the double-wound line relay 40 of the connector repeater D.

65 When the calling line is extended to the

switch D as above described, the line relay 40 is energized over the line circuit in the usual manner and completes a circuit for the slow to release relay 41. Upon energizing, the latter relay prepares a circuit for the vertical magnet 49 at armature 57, and at armature 56 connects ground to the release trunk conductor 85, thereby closing a holding circuit for the line switch C which extends by way of the test contact 25, test wiper 22, armature 19 and its working contact, winding of the switching relay 14, and the winding of the stepping magnet 15 to battery. The above circuit is completed before the slow acting line relay 13 has had time to deenergize and serves to maintain the switching relay 14 energized throughout the connection. Ground is also extended by way of the private normal conductor 30 to multiple connected test contacts in the banks of the connector repeaters, whereby the said line is made busy.

The calling subscriber at station A may now proceed to operate his calling device 7 in accordance with the digits in the telephone number of substation A'. When the calling device is operated for the first digit 0, a series of ten interruptions is produced in the line circuit, to which the line relay 40 responds by deenergizing a corresponding plurality of times. At the first deenergization the line relay transmits a current impulse to the vertical magnet 49 over the following path: grounded armature 54 and its resting contact, armature 57 and its working contact, resting contact and off normal spring 53, winding of the slow to release series relay 42, and winding of the vertical magnet 49 to battery. The above is the circuit over which the first impulse is transmitted. At the first upward movement of the shaft the normal springs are shifted and the circuit is completed over a new path which is the same as the one previously traced except that it includes the normally open contact controlled by spring 53 and armature 58 of the series relay 42 and its working contact, the said series relay being now in operated position. By the operation of the vertical magnet 49 the wipers 75-77, inclusive, are raised step by step until they stand opposite the level of bank contacts in which is located the set of contacts associated with the line including substation A', which in this case is the tenth or "0" level. The slow to release series relay 42, which is energized in series with the vertical magnet, maintains its armature attracted throughout the vertical operation of the switch, and at the end of the vertical movement deenergizes and transfers the operating circuit to the rotary magnet 50.

When the wipers are raised to the "0" level, the shaft controlled spring 84 is brought into engagement with its working

contact by the operation of the shaft. This may be accomplished by any suitable cam arrangement. A circuit is thereby completed for relay 44 in series with the lower 5 winding of the ring cut off relay 45. Both these relays are energized and the latter relay disconnects the ringing current at armature 63, extends the talking conductors to the armatures 70 and 74 at armatures 61 10 and 63, and locks itself up over the release trunk conductor 85 at armature 62. Relay 44, upon energizing, connects the two windings of the impedance coil 43 in bridge 15 of the talking conductors in an obvious manner.

The calling subscriber may now operate his calling device in accordance with the second digit 4 in the desired number. As before, a series of interruptions is produced 20 in the line circuit to which the line relay 40 again responds by transmitting a series of four impulses to the rotary magnet 50 over the following path: grounded armature 54 and its resting contact, armature 57 25 and its working contact, resting contact and normally open contact controlled by off normal spring 53, armature 58 and its resting contact, resting contact and armature 66, armature 73 and its resting contact, and 30 the winding of the rotary magnet 50 to battery. Responsive to these impulses the rotary magnet is operated to rotate the switch wipers into engagement with the fourth set 35 of bank contacts, in which the line including the substation A' terminates, these bank contacts being indicated in the drawing by reference characters 78, 79 and 80. The slow to release relay 47 is energized in parallel with the rotary magnet and remains 40 in operated position while the switch wipers are being rotated. At its armature 68, relay 47 connects the test wiper 76 to the winding of the test relay 46, and at its armature 69 relay 47 closes the operating circuit 45 for the rotary magnet over a path which is independent of the contacts controlled by armature 66 of the test relay 46. This latter operation is to guard against the possibility of the circuit for the rotary magnet 50 being opened at armature 66 in case the test relay is energized due to the test wiper 76 passing over busy test contacts. Assuming first that the line including substation A' is busy when connection thereto is established as just described, the test wiper 76, 55 when it comes to rest in engagement with the test contact 79, will find a ground potential thereon and the test relay 46 will be operated. Upon energizing, the test relay 60 prepares a locking circuit for itself at its armature 65 (completed when relay 47 de-energizes), and at its armature 64 connects a lead from the busy signalling machine to the lower heavy talking conductor. By this 65 means the calling subscriber is given an au-

dible busy signal, and being advised thereby what the desired line is for the time being inaccessible, he will hang up his receiver and release the connection.

Having described the operations which take place when the called line is busy, it will now be assumed that the called line is idle when the connection is attempted. Under these circumstances, when the test wiper 76 comes to rest in engagement with test 75 contact 79 it will not find ground potential and the test relay 46 will not be energized. Then when the slow to release relay 47 de-energizes at the end of the rotary movement 80 of the switch a multiple circuit will be completed as follows: from the grounded release trunk conductor 85, by way of armature 65 and its resting contact, lower winding of switching relay 48, resting contact and armature 68, normally closed contact controlled by armature 71, test wiper 76, and test contact 79 to a point where the circuit branches two ways, one branch extending by 85 way of private normal conductor 121, resting contact and armature 138, and the winding of relay 124 to battery; while the other branch extends by way of private normal conductor 101, the winding of switching relay 104, and the winding of stepping magnet 105 to battery. Upon the closure of the 90 above circuit relays 104, 48 and 124 are energized and the latter relay is operated to prepare the circuit of line relay 123 in the individual line repeater R. At the line switch C' the switching relay 104 is operated to 100 clear the line of substation A' of its normal battery and ground connections. This relay operates only about half way, due to the fact that the line relay 103 has not been energized, and the line conductors are not connected through to the wipers of the line switch. At the connector repeater D when the switching relay 48 is energized the said relay establishes a locking circuit for itself 105 at its armature 72, connects direct ground to the test wiper 76 at armature 71, opens the rotary magnet circuit at armature 73, and at armatures 70 and 74 connects up the line wipers 75 and 77. At the individual line repeater R the line 115 relay 123 is now energized over a circuit traceable from ground by way of the lower winding of line relay 123, working contact and armature 132, lower left-hand winding of repeating coil I, line conductor 122, bank 120 contact 80, wiper 77, working contact and armature 74, armature 63 and its working contact, armature 55 and its working contact, lower winding of impedance coil 43, armature 60 and its working contact, working contact and armature 59, upper winding of impedance coil 43, resting contact and armature 67, working contact and armature 61, armature 70 and its working contact, 125 wiper 75, bank contact 78, line conductor 130

120, working contact and armature 130, upper left-hand winding of repeating coil I, armature 131 and its working contact, and upper winding of line relay 123 to battery. 5 Relay 123, upon energizing, closes a circuit for slow to release relay 126 at armature 129. Release relay 126, upon energizing, prepares a circuit for the slow to release ringing relay 128 at armature 137, and at 10 armature 135 connects ground to conductor 121.

The connection having been finally completed the ringing arrangement will now be explained. The calling subscriber may now 15 operate his calling device in accordance with the third digit 0, or the first, and in this case, the only code ringing digit. As before, a series of ten interruptions is produced in the line circuit to which the line relay 40 again 20 responds; this time, however, by transmitting a series of ten interruptions to the line relay 123 of the repeater R by opening and closing its circuit at armature 55. Responsive to these interruptions the line relay 123 25 transmits a series of ten impulses to the ringing relay 128 over a path traceable from grounded armature 134 and its resting contact, armature 141 and its resting contact, armature 137 and its working contact, and winding of relay 128 to battery. Relay 128, being slow to release, holds up during the 30 impulsing and connects generator GEN. and ground to conductors 151 and 152 at armatures 139 and 140, respectively, whereby 35 ringing current is projected out over the line including substation A' to operate the bridged ringers for a relatively long interval in accordance with the digit dialled, which corresponds to the maximum number 40 of impulses. If the called subscriber does not answer upon the first code ring of his bell, the calling subscriber may ring his bell again by merely re-dialling the ringing code number, and may repeat this operation 45 as many times as desired as long as the receiver is held off the switch-hook. The called subscriber at station A' upon hearing his code ring will lift his receiver, bridging same across the line, and when the ringing relay 128 releases its armatures the talking connection will be finally completed. A 50 further result of the lifting of the receiver is the closing of a circuit for impulsing relay 125 which may be traced from ground, impulse springs of the calling device 166, working contact and spring 169, bell 165, line conductors 151 and 152, upper and lower right hand windings of repeating coil I, and relay 125 to battery. Relay 125, upon 55 energizing, further opens the circuit of ringing relay 128 at armature 134 to prevent ringing on the line when the receiver is off the switchhook.

The desired connection has now been 60 established. The transmitter at the calling

substation A is supplied with talking battery through the windings of the line relay 40, while the transmitter at substation A' is supplied with talking battery locally through the primary winding of the induction coil 70 167. The voice currents take the path shown in heavy lines which will be understood without further explanation.

When the subscribers are through talking, they will both replace their receivers, 75 and the replacement of the receiver at substation A causes the line switch C and the connector repeater D to be released in the following manner: When the line circuit is broken by the replacement of the receiver 80 the line and release relays 40 and 41 are both deenergized, and a circuit is completed for the release magnet 51 which operates to restore the connector repeater D to normal position in the well known manner. Relay 85 41 also disconnects ground from the release trunk conductor 85 thereby permitting the switching relay 14 of the line switch C to de-energize. By the deenergization of relay 14 the line switch C is restored to normal condition ready for another call. When the connector repeater D restores to normal position the circuit of line relay 123 of the individual line repeater R is broken, whereupon 90 said relay deenergizes and opens the circuit of relay 126. Relay 126, upon deenergizing, removes ground from the release trunk conductor 121 thereby permitting the switching relay 104 of the line switch C' to de-energize. By the deenergization of relay 100 104 the line switch C' is restored to normal condition ready for another call. The replacement of the receiver at substation A' completes the releasing of the individual line repeater R by breaking the circuit of impulsing relay 125, whereby said relay deenergizes, and the repeater is also ready for 105 another call.

The subscriber at station A may obtain 110 connection with the subscriber at station A' by removing his receiver and dialling the directory number of the substation A', which we will assume to be 04-2. The first two digits being those which control the line selection, the connector-repeater D will raise its 115 wipers up opposite the tenth level and rotate them in to the fourth set of bank contacts or to the contacts of the desired line in response to the dialling of these digits by the calling subscriber as already explained. 120 The calling subscriber may now dial the third digit 2, whereupon two interruptions are produced in the line circuit, to which the line relay of the connector-repeater responds by transmitting two interruptions to the line 125 relay of the repeater. Responsive to these interruptions the line relay of the repeater transmits two impulses to the ringing relay which operates to project ringing current out over the line including substation A' to 130

operate the bridged ringers for a relatively short interval in accordance with the digit of few impulses.

The subscriber at station A may obtain connection with the subscriber at station A' in the same way by dialling the directory number of the substation A', which we will assume to be 04-02. The first two digits control the selection of the desired line, as already explained. The last two digits control the code ringing, the 0 causing a long ring while the 2 causes a short ring as has also been already explained.

It will be understood that there may be other stations on the line which are signalled in a similar manner according to codes made up of long and short rings in different combinations.

Having described the process of setting up a connection between a straight line automatic substation and a plurality of magneto local battery substations on a line, the reverse will now be described. For this purpose it will be assumed that the subscriber at station A' desires to obtain connection with the subscriber at station A. In order to do this, the subscriber A' removes his receiver and dials the directory number of the subscriber A.

When the receiver is removed at substation A', it and the secondary winding of the induction coil 167 are bridged across the line, while a simplex dialling circuit is completed over the line conductors for the line relay of the individual line repeater which may be traced from ground at the calling device 166, working contact and switch-hook spring 169 to the center point of the bell 165 where it divides and extends over the line conductors 151 and 152, armatures 139 and 140 and their resting contacts, the right hand windings of the repeating coil I, and impulsing relay 125 to battery. Upon energizing, the impulsing relay 125 closes a circuit at armature 134 for relay 127 whereupon this relay energizes and actuates its armature 138 to prevent a circuit from being closed for relay 124 when ground is placed on the holding trunk by the individual line switch. A further result of the energization of impulsing relay 125 is the closing of a circuit at armature 133 for line relay 103 of the line switch C' which may be traced from ground, resting contact and armature 110, conductor 102, conductor 122, lower left hand winding of repeating coil I, armature 132 and its resting contact, upper left hand winding of repeating coil I, working contact and armature 133, conductor 120, conductor 100, armature 108 and its resting contact, and through line relay 103 to battery. The operation of line switch C' is identical with that of line switch C already explained and need not, therefore, be repeated here. It may be assumed, however, that when the call is

initiated the wipers of the line switch C' are rotated step by step until they come to rest on the idle bank contacts of the trunk line shown in the drawing. Under these circumstances the switching relay 104 energizes and extends the line conductors 100 and 102 to the upper and lower windings of the double wound line relay 40 of the connector repeater D.

When the calling line is extended to the switch D as above described, this switch operates in the manner already described to prepare a circuit for the vertical magnet; connect ground to the release trunk, thereby closing a holding circuit for the line switch C'; and to extend ground to multiple connected test contacts in the banks of the connector repeaters which have access to the line including substation A', whereby the said line is made busy.

The calling subscriber at station A' may now proceed to operate his calling device 166 in accordance with the digits in the local telephone number of substation A. When the calling device is operated for the first digit a series of interruptions is produced in the simplex dialling circuit; to which the impulsing relay 125 responds by deenergizing a corresponding plurality of times. The deenergization of impulsing relay 125 causes a corresponding deenergization of line relay 40 of connector-repeater D by interrupting its circuit at armature 133. The circuit of relay 127 is likewise interrupted at armature 134, but being slow to release, this relay holds up during the dialling operation. The line relay 40 in turn transmits a corresponding series of impulses to the vertical magnet to raise the switch wipers step by step until they stand opposite the level of bank contacts in which is located the set of contacts associated with the line of substation A, which in this case we will assume to be other than the tenth level. The slow to release series relay, which is energized in series with the vertical magnet, maintains its armature attracted throughout the vertical operation of the switch, and at the end of the vertical movement deenergizes and transfers the operating current to the rotary magnet, as has already been explained in connection with a call originating at substation A.

The calling subscriber may now operate his calling device in accordance with the second digit in the desired number. As before, a series of interruptions is produced in the simplex dialling circuit, to which the impulsing relay 125 again responds and in turn causes a corresponding series of interruptions in the circuit including line relay 40. The relay 40 again responds by transmitting a series of impulses to the rotary magnet which is operated to rotate the switch wipers into engagement with the

particular set of bank contacts in which the line including the substation A terminates as previously explained. The bank contacts in which the line terminates are indicated in the drawing by reference characters 81, 82 and 83. As previously explained in connection with test wiper 79, the test wiper 82 is now connected to the test relay which tests for the busy or idle condition of the called line. If busy, the busy signalling machine is connected to the lower heavy talking conductor and by means of this and the repeating coil I at the individual line repeater R the calling subscriber is given an audible busy signal. If the line is idle it is cleared of its normal battery and ground connections in the line switch C and the interrupted generator machine is connected to the called line by the switching relay, the ring cut-off relay 45 now being deenergized, to project ringing current intermittently out over the line in the usual manner to operate the bridged bell at the substation A. It will be understood that the return path for the ringing current includes the upper winding of the ring cut-off relay 45 and when the called subscriber responds by removing his receiver the ring cut-off relay is energized and establishes a locking circuit for itself at its armature 62. The ring cut-off relay also opens the ringing circuit at its armatures 61 and 63, and at the working contacts of these armatures finally completes the talking connection.

The desired connection has now been established. The transmitter at the calling substation A' is supplied with talking battery locally through the primary winding of the induction coil 167, while the transmitter at the substation A is now supplied with talking battery through the windings of the double wound back bridge impedance coil 43.

When the subscribers are through talking they will both replace their receivers. The replacement of the receiver at substation A' causes the individual repeater R, the line switch C', and the connector-repeater D to be released in the following manner: When the circuit of impulsing relay 125 is broken by the replacement of the receiver, this relay deenergizes to restore the individual line repeater R to normal condition and to break the circuit including the line relay 40 of the connector-repeater D. The line relay 40, upon deenergizing, causes the release relay 41 to deenergize, whereupon the two relays in their deenergized condition complete a circuit for the release magnet 51 which operates to restore the connector-repeater D to normal position in the well understood manner. Relay 41 also disconnects ground from the release trunk conductor 85, thereby permitting the switching relay 104 of the

line switch C' to deenergize. By the de- 65 energization of relay 104 the line switch C' is restored to normal condition ready for another call.

An explanation of the manner in which a subscriber on the line having a plurality of 70 substations thereon can call any other subscriber thereon may now be proceeded with. The subscriber at station A' who desires to connect with another subscriber on his line will, therefore, remove his receiver to determine if the line is busy or not and if found idle will operate his hand generator 170 in accordance with the ringing code of the desired substation. When the receiver is removed the impulsing relay of the individual 75 line repeater R operates to cause the line switch C' to select an idle connector-repeater, whereupon ground potential is extended by way of the private normal conductor to multiply connected test contacts in the banks 80 of the connector-repeaters which have access to the line including substation A', whereby the said line is made busy, as previously explained. The called subscriber upon hearing his code ring will respond by removing his receiver, whereupon the subscribers 85 may hold conversation, their transmitters being supplied with talking battery locally.

When the subscribers are through talking 90 they will both replace their receivers, whereupon the individual repeater R, the line switch C', and the selected connector-repeater will be released in the manner already described.

Having described my invention, what I 100 consider to be new and desire to have protected by Letters Patent will be pointed out in the appended claims.

What is claimed is:

1. In a telephone system, a line, a party line having an individual line repeater, an automatic switch for connecting said lines, a source of ringing current at said repeater, and means controlled by the subscriber on said first line for causing said repeater to variably connect said source to said party line for selectively signalling the parties thereon.

2. The combination, with an individual line repeater for selectively ringing on a party line, of a ringing relay responsive to digits dialled by the calling subscriber for connecting generator to said party line for a short or long period depending upon whether said digits are short or long.

3. In a telephone system, means including an automatic switch for connecting a calling and called line, an individual line repeater for the called line, a ringing relay, means controlled by the calling subscriber for energizing said relay for a short or long period, depending upon the digit dialled, an impulsing relay responsive to the lifting of the

receiver at the called substation, and a circuit for said ringing relay opened by said impulsing relay.

4. In a telephone system, individual lines, a party line, a connector switch operable to connect with any desired one of said lines, automatic ringing equipment associated with said connector for signalling an individual line when the same is connected with, and means for automatically rendering said equipment ineffective when said party line is connected with.

5. In a telephone system, individual lines, a party line, a connector switch operable to connect with any desired one of said lines, automatic ringing equipment associated with said connector for signalling an individual line when the same is connected with, means for automatically rendering said equipment ineffective when said party line is connected with, and other ringing equipment controlled at the will of the calling party for signalling the stations on said party line.

6. In a telephone system, individual lines, a party line, a connector switch operable to connect with any desired one of said lines, automatic ringing equipment associated with said connector for signalling an individual line when the same is connected with, means for automatically rendering said equipment ineffective when said party line is connected with, ringing equipment individual to said party line, and means in said connector for controlling said individual ringing equipment.

7. In a telephone system, means including an automatic switch for connecting a calling and a called line, a calling device at the calling station for controlling said switch in accordance with digits in the called number, and a ringing relay individual to the called line controlled by said calling device in accordance with other digits in the called number.

8. In a telephone system, means including an automatic switch for connecting a calling and a called line, a calling device at the calling station for controlling said switch in accordance with digits in the called number, a ringing machine, a ringing relay for connecting said ringing machine to the called line for long or short intervals, and means controlled by said calling device when the same is operated in accordance with another digit for causing a long or short energization of said relay depending on the value of the digit dialled.

9. In a telephone system, means including an automatic switch for connecting a calling and a called line, a calling device at the calling station for controlling said switch in accordance with digits in the called number, a ringing relay individual to the called line for projecting ringing current out over the called line for long or short intervals, and

means controlled by said calling device when the same is operated in accordance with an additional digit or digits for energizing said relay during periods of time directly proportional to the value of the digits dialled.

10. In a telephone system, means including an automatic switch for connecting a calling and a called line, a calling device at the calling station for controlling said switch in accordance with digits in the called number, a ringing relay individual to the called line, and means responsive to said calling device when the same is operated in accordance with another digit for energizing said ringing relay while impulses are being transmitted.

11. In an automatic telephone system, a ringing relay individual to the called line for connecting a source of ringing current to the called line, and means responsive to impulses generated by the calling device at the calling station for energizing said relay while said impulses are being transmitted.

12. In an automatic telephone system, a connector, a line relay for controlling said connector to connect with a called line, and a ringing relay individual to the called line controlled by said line relay.

13. In an automatic telephone system, a connector, a line relay for controlling said connector to connect with a called line, a ringing relay individual to the called line controlled by said line relay, and a second relay individual to the called line for breaking the circuit of said line relay.

14. An automatic telephone system comprising individual and party lines, connectors common to said lines, means in each connector for signalling the individual lines but not the party lines, signalling means individual to each party line, and means in each connector for controlling the said individual signalling means.

15. In an automatic telephone system, a ringing machine, a ringing relay for connecting said ringing machine to a called line, and means responsive to dialing impulses generated at the calling station for continuously energizing said relay while said impulses are being transmitted.

16. In a telephone system, a connector switch operable responsive to two digits dialled by a calling subscriber to connect with any desired line terminating in its banks, automatic ringing equipment associated with said connector effective to signal the line connected with when said line terminates in a certain level of the banks of said connector, and means for automatically rendering said equipment ineffective when the line connected with terminates in a certain other level of the banks of said connector.

17. In a telephone system, a connector switch operable to connect with any desired

line terminating in its banks, automatic ringing equipment associated with said connector effective to signal the line connected with when said line terminates in a certain level 5 of the banks of said connector, means for automatically rendering said equipment ineffective when the line connected with terminates in a certain other level of the banks of said connector, and other ringing equipment controlled at the will of the calling subscriber for signalling the line connected with when first said ringing equipment is rendered ineffective.

18. In a telephone system, means including 15 an automatic switch for connecting a calling and a called line, a calling device at

the calling station for directly controlling said switch in accordance with two digits in the called number, a ringing machine common to said switch and other similar switches, a ringing relay for connecting said ringing machine to the called line for long or short intervals, and means controlled by said calling device when the same is operated in accordance with another digit for causing a long or short energization of said relay depending on the value of the digit dialled.

In witness whereof, I hereunto subscribe my name this 26th day of November, A. D., 1924.

ARTHUR J. RAY.
